[57] CLAIM

The ornamental design for a manifold, as shown and described.

DESCRIPTION

FIG. 1 is a perspective view of the front and top of one embodiment of a manifold showing our new design;

FIG. 2 is an elevational, side view of the embodiment of FIG. 1, the other side view being identical;

FIG. 3 is a front elevational view of the embodiment shown in FIG. 1;

FIG. 4 is a top, plan view of the embodiment shown in FIG. 1;

FIG. 5 is a rear, elevational view of the embodiment shown in FIG. 1;

FIG. 6 is a bottom, plan view of the embodiment shown in FIG. 1;

FIG. 7 is a perspective view of the front and top of another embodiment of a manifold showing our new design;

FIG. 8 is an elevational view of one side view of the embodiment shown in FIG. 7, the other side view being identical;

FIG. 9 is a front, elevational view of the embodiment shown in FIG. 7;

FIG. 10 is a top, plan view of the embodiment shown in FIG. 7;

FIG. 11 is a rear, elevational view of the embodiment shown in FIG. 7; and,

FIG. 12 is a bottom, plan view of the embodiment shown in FIG. 7.
